a corporation of New York

Application June 9, 1948, Serial No. 31,855

7 Claims. (Cl. 122—1)

1

This invention relates to heat exchange apparatus and more particularly to apparatus for heating air.

The present invention provides apparatus whereby air to support combustion in a furnace is heated by flowing in indirect heat exchange relationship with liquid, which liquid has been heated by passing in indirect heat exchange relationship with gases of combustion from the furnace.

This invention further provides heat exchange apparatus in which heated circulating liquid is used to heat air and wherein the volume of circulating liquid is varied in accordance with the temperature of the liquid.

The present invention also provides an air heater whereby air to support combustion in a vapor generator is heated by flowing in indirect heat exchange relationship with liquid which liquid has been heated by passing in indirect heat exchange relationship with gases of combustion from the furnace and wherein the rate of flow of liquid passing in indirect heat exchange relationship with the gases of combustion and with the air corresponds to the flow of vapor from the vapor generator.

The invention will be understood from the following description when considered in connection with the accompanying drawings forming a part thereof, and in which:

Fig. 1 is a transverse vertical sectional view taken on the line 1—1 of Fig. 2;

Fig. 2 is a plan view partly in elevation and partly in section taken on the line 2—2 of Fig. 1;

Fig. 3 is a flow diagram of the apparatus of the present invention, and

Fig. 4 is a partial transverse vertical sectional view of another embodiment of the invention.

Like characters of references refer to like parts throughout the several views.

Referring to the drawings, the apparatus of the present invention is disclosed as embodied in a vapor generator comprising a setting 10 with an upper steam and water drum 11 associated therewith. The setting 10 has a combustion chamber 10' therein, which chamber is fired by a plurality of burners 12. A vertically inclined bank of vapor generator tubes 13 is disposed at one side of chamber 10', the tubes of which bank are in communication at the top thereof with the liquid space of drum 11 and at the bottom with a liquid drum 14 which is offset to said one side of drum 11. A superheater 15 is positioned within the bank of tubes 13 which superheater has an inlet 16 (Fig. 2) in communication with a vapor out-

let conduit 17 connected to the vapor space of steam and water drum 11. Superheater 15 has an outlet 15' (Fig. 2) in communication with superheated steam outlet conduit 18 (Fig. 1). The roof 19 of setting 10 and the side wall 20 of said setting are lined by water wall tubes 21, which tubes are in communication at the upper end thereof with the liquid space of drum 11 and at the bottom with a header 22.

An outlet flue 22' providing a combustion gas outlet passage 23 is positioned at the side of the bank of tubes 13 opposite to the side of said bank adjacent combustion chamber 10'. Passage 23 of flue 22' is in communication with the setting at the top thereof so that gases of combustion from chamber 11 after flowing in heat exchange relationship with the bank of tubes 13 pass from the setting in passage 23 of flue 22'.

As shown, an economizer section 24 is positioned in passage 23 of flue 22' in the lower part of said flue, while a heat exchanger 25 comprising a plurality of superimposed spaced rows of spaced tubes 26 is disposed in passage 23 above economizer 24. The tubes 26 extend transversely of passage 23 so that gases of combustion flowing through the passage flow over said tubes. The tubes of each row 26 are serially connected as are the adjacent rows of the superimposed rows of tubes. The heat exchanger 25 has a fluid inlet 27 in communication with the uppermost row of tubes and a liquid outlet 28 in communication with the lowermost row of tubes. Liquid inlet 27 is in communication with the bottom of reservoir tank 29 through conduit 27'. As shown, the tubes of economizer 24 and the tubes of heat exchanger 25 have extended surface members thereon.

Tank or reservoir 29, which is pressure-tight, is mounted above drum 11 on supporting girders 30. As shown, the tank 29 has a safety valve 31 and a vent 32 at the top thereof and also has a liquid gage 33 at one side of the tank. In order that the liquid flowing through heat exchanger 25 will not be vaporized in said heat exchanger, it is necessary to provide means for maintaining the liquid under such pressure that it will not boil while it is being circulated from the reservoir 29 through the heat exchanger 25 and into the tubes 46 of air heating heat exchanger 45. As shown in Fig. 1, this is accomplished by providing a heating coil disposed slightly below the normal water level WL and above a baffle 29' having an opening 70 therein. The relatively small quantity of liquid between WL and baffle 29' is thereby heated. Coil 34 has a steam inlet

35 through which either saturated or superheated steam is passed into the coil and flows outwardly thereof, after passing in indirect heat exchange relationship with the liquid in tank 29, through outlet 36. The steam passed through coil 34 is of such temperature that the liquid between WL and baffle 29' is heated to a degree corresponding to the pressure required on the liquid passing through exchanger 25 to avoid boiling. The baffle 29' prevents a substantial mixing of the relatively small quantity of liquid above the baffle with the larger quantity of circulating liquid below said baffle. The temperature of the liquid above baffle 29' is controlled by controlling the flow of steam through inlet 35 into coil 34. 15 As shown, a valve 71, which may be manually or automatically controlled is positioned in inlet 35 and sufficient steam is permitted to flow through coil 34 to heat the liquid above baffle 29' to a degree substantially equal to the temperature of the liquid leaving heat exchanger 25 through outlet 28.

An air conduit comprising a top wall 31, an end wall 38, a bottom wall 39, a forward wall 40, and a rear wall 41 is disposed along the front wall 42 of setting 10 in which front wall of the setting the burners 12 are disposed. Each of the burners 12 have air inlet ports 43 through which air to support combustion enters chamber 10'. The air conduit has an inlet passage 44 through which air enters said passage. An air heating heat exchanger 45 comprising a plurality of tubes 46 is disposed in the air conduit in the path of flow of air from inlet passage 44 to ports 43 of burners 12. As shown, tubes 46 are vertically extending and arranged in a plurality of closely adjacent rows, the tubes in each row being spaced from one another and the tubes of each row being spaced from the tubes of adjacent rows. Tubes 46 are connected at the top thereof to an inlet header 47 and at the bottom to an outlet header 48. Inlet header 47 is in communication with outlet 28 of heat exchanger 25 through a heated fluid conduit 49. Outlet header 48 of air heating heat exchanger 45 communicates with the suction of a pump 50 through outlet conduit 51. The discharge of pump 50 communicates with the liquid space of tank 29 through liquid conduit 52. As shown, the pump 50 is actuated by an electric motor 53.

The flow of liquid from the tank or reservoir 29 through heat exchangers 25 and 45 is controlled in response to the flow of vapor from the vapor generator through superheated steam outlet conduit 18. As shown, this control comprises a pressure responsive device 55 in communication with conduit 18 at one side of an orifice 56 through pipe 57 and at the other side of said outlet through pipe 58. The pressure differential at opposite sides of the orifice 56 which is transmitted to opposite sides of a diaphragm 59 in device 55 actuates the diaphragm which in turn moves a contact arm 60 of a rheostat 61. The rheostat is in communication with one pole of an electrical source through line 62 and with a connection of motor 53 through line 63 which line is connected to arm 60. The other connection of motor 53 communicates with opposite pole of said electrical source through line 64.

In operation, vapor is generated in the vapor generator by the flow of combustion gases from chamber 10' over bank of tubes 13 into passage 23 of outlet flue 22'. Vapor generated in the tubes 13 passes into drum 11 thence into vapor outlet conduit 17 to thereafter flow into super-

heater 15 through superheater inlet 16. Passage of gases of combustion in heat exchange relationship with the superheater 15, as the gases flow to flue 22', superheats the steam passing through said superheater. The superheated steam flows outwardly of the superheater through superheated steam outlet 15' and outlet conduit 18.

Liquid, for example, water, or a high boiling point liquid such as diphenyl, diphenyl oxide or other desirable liquid in reservoir 29 above baffle 29' is heated to the desired temperature, that is, to a temperature above that of the liquid flowing through outlet 28 of heat exchanger 25, by flowing steam through coil 34. This creates sufficient pressure on the liquid in tank or reservoir 29 to prevent boiling of the liquid in heat exchanger 25. From tank 29, liquid under pressure flows downwardly through inlet conduit 21' into heat exchanger 25. The liquid thereafter flows through the heat exchanger 25 to liquid outlet 28 and is heated in the heat exchanger by passage in indirect heat exchange relationship with gases of combustion flowing through passage 23 of flue 22'. The heated liquid passes from outlet 28 into heated fluid conduit 49 whence it flows into inlet header 47 of the air heating heat exchanger 45. From the inlet header 47, the heated liquid passes through tubes 46 of heat exchanger 45 into outlet header 48 and is withdrawn from said header by pump 50 which withdraws the liquid from the heater through outlet conduit 51 thereafter to discharge the liquid through liquid conduit 52 into reservoir 29.

Air to be heated is passed into the air conduit through inlet passage 44 and flows in indirect heat exchange relationship with tubes 46 of air heating heat exchanger 45 and is thereby heated. After heating, the air flows through ports 43 of burners 12 into the combustion chamber 10'.

The flow of liquid from the reservoir 29 through heat exchangers 25 and 45 and thence back to the reservoir is controlled in response to the flow of steam through superheater outlet conduit 18. For example, upon an increase in the flow of steam through outlet conduit 18, there is an increase of pressure across the orifice 56 which increased pressure influences pressure responsive device 55 through pipe 57 to cause rheostat arm 60 to move in a clockwise direction thereby permitting a greater flow of current through line 62 to rheostat 61, arm 60, and line 63 to electric motor 53. Increased flow of current to motor 53 increases the speed of the motor and the pump 50 thereby increasing the rate of circulation of the liquid from the tank 29 through heat exchangers 25 and 45 and through the line 52 to tank 29. Upon a decrease in the flow of steam through outlet conduit 18, the pressure responsive device 55 would cause the arm 60 of rheostat 61 to move in a counterclockwise direction causing the resistance of rheostat 61 to be increased and a lesser amount of current to pass to motor 53 thereby decreasing the speed of pump 50 and the rate of circulation of liquid through heat exchangers 25 and 45. It will be understood that other flow controlling devices which control the rate of flow of fluid from reservoir 29 through heat exchangers 25 and 45 in response to the flow of steam through steam outlet 18 may be used.

In the form of the invention shown in Fig. 4, the tank 29 is of cylindrical shape and does not require a baffle 29' as shown in Fig. 1. Liquid

from the lower portion of the tank passes into an outlet conduit 72 which outlet conduit is in communication at one end thereof with the lower portion of the tank and at the other end with conduit 27'. Intermediate the opposite ends thereof, the outlet conduit 72 is in communication with liquid conduit 52.

In operation, liquid from tank 29 passes therefrom through conduit 72 in which conduit it mixes with fluid from air heat exchanger 45 passed to conduit 72 through liquid conduit 52. The mixture of liquid then flows from outlet conduit 72 into inlet conduit 27' thence into the inlet 27 of heat exchanger 25. Substantial mixing of the liquid adjacent the normal water level WL in the upper part of tank 29, which liquid is heated by coil 34, with the liquid circulating through conduits 52, 72 and 27' is prevented.

Inasmuch as changes may be made in the form, location, and relative arrangement of the several parts of the apparatus disclosed without departing from the essential characteristics of the invention, it will be understood that the invention is not to be limited excepting by the scope of the appended claims.

What is claimed is:

1. Heat exchange apparatus for heating a fluid by flowing said fluid and a liquid in indirect heat exchange relationship with one another, said apparatus comprising means forming a flow path for heated gases, a heat exchanger providing a liquid path of flow and positioned in indirect heat exchange relationship with heated gases passing through said gas flow path, a pressure-tight liquid reservoir so constructed and arranged that liquid therein is normally maintained under pressure, a heating coil within said reservoir below the normal liquid level therein adapted to vaporize liquid in indirect heat exchange relationship with said coil and thereby create pressure in the reservoir, means through which liquid is conducted from the reservoir into said liquid path of flow of the heat exchanger, a fluid conduit for conducting fluid to be heated, another heat exchanger providing a liquid path of flow with a liquid inlet and a liquid outlet, the other heat exchanger being positioned in indirect heat exchange relationship with fluid flowing in the fluid conduit for conducting fluid to be heated, means for conducting heated liquid from the first-mentioned heat exchanger to the inlet of the liquid path of flow of the other heat exchanger, conduit means in communication with the outlet of said other heat exchanger and with the liquid path of flow of the first-mentioned heat exchanger, circulating means associated with said last-mentioned conduit means for circulating liquid therethrough and control means associated with the heating coil and adapted to control the generation of vapor and pressure within the reservoir to maintain the liquid therein below its boiling point.

2. Heat exchange apparatus for heating a fluid by flowing said fluid and a liquid in indirect heat exchange relationship with one another, said apparatus comprising means forming a flow path for heated gases, a heat exchanger providing a liquid path of flow and positioned in indirect heat exchange relationship with heated gases passing through said gas flow path, a pressure-tight liquid reservoir having a top and bottom and a normal liquid level intermediate said top and bottom, said reservoir being so constructed

and arranged that liquid therein is normally maintained under pressure, a heating coil within said reservoir below the normal liquid level and above said bottom of the reservoir, a baffle disposed above the bottom of the reservoir and below the said heating coil, the baffle dividing the reservoir into upper and lower compartments and having a liquid opening therein through which said compartments communicate with one another, said coil being adapted to vaporize the liquid in the upper compartment and thereby create pressure in the reservoir, means through which liquid is conducted from the lower part of the reservoir into said liquid path of flow of the heat exchanger, a fluid conduit for conducting fluid to be heated, said fluid conducting means having a fluid inlet and a fluid outlet, another heat exchanger providing a liquid path of flow with a liquid inlet and a liquid outlet, the other heat exchanger being positioned in indirect heat exchange relationship with fluid flowing in the fluid conduit for conducting fluid to be heated, means for conducting heated liquid from the first-mentioned heat exchanger to the inlet of the liquid path of flow of the other heat exchanger, in communication with the outlet of said other heat exchanger and with the liquid path of flow of the first-mentioned heat exchanger, circulating means associated with said last-mentioned conduit means for circulating liquid therethrough, and control means associated with the heating coil and adapted to control the generation of vapor and pressure within the reservoir to maintain the liquid therein below its boiling point.

3. Heat exchange apparatus for heating a fluid by flowing said fluid and a liquid in indirect heat exchange relationship with one another, said apparatus comprising means forming a flow path for heated gases, a heat exchanger providing a liquid path of flow and positioned in indirect heat exchange relationship with heated gases passing through said gas flow path, a pressure-tight liquid reservoir having a top and bottom and a normal liquid level intermediate said top and bottom, said reservoir being so constructed and arranged that liquid therein is normally maintained under pressure, a steam heating coil within said reservoir below the normal liquid level and above said bottom of the reservoir, said coil having a steam inlet and a steam outlet, means for controlling the flow of steam through said coil to control the generation of vapor and pressure within the reservoir to maintain the liquid therein below its boiling point, a baffle disposed above the bottom of the reservoir and below the said heating coil, the baffle dividing the reservoir into upper and lower compartments and having a liquid opening therein through which said compartments communicate with one another, said coil being adapted to vaporize the liquid in the upper compartment and thereby create pressure in the reservoir, means through which liquid is conducted from the lower part of the reservoir into said liquid path of flow of the heat exchanger, a fluid conduit for conducting fluid to be heated, said fluid conducting means having a fluid inlet and a fluid outlet, another heat exchanger providing a liquid path of flow with a liquid inlet and a liquid outlet, the other heat exchanger being positioned in indirect heat exchange relationship with fluid flowing in the fluid conduit for conducting fluid to be heated, means for conducting heated liquid from the first-mentioned heat exchanger to the inlet

of the liquid path of flow of the other heat exchanger, conduit means in communication with the outlet of said other heat exchanger and with the liquid path of flow of the first-mentioned heat exchanger, and circulating means associated with said last-mentioned conduit means for circulating liquid therethrough.

4. Heat exchange apparatus for heating a fluid by flowing said fluid and a liquid in indirect heat exchange relationship with one another, said apparatus comprising means forming a flow path for heated gases, a heat exchanger providing a liquid path of flow and positioned in indirect heat exchange relationship with heated gases passing through said gas flow path, a pressure-tight liquid reservoir so constructed and arranged that liquid therein is normally maintained under pressure, a heating coil within said reservoir below the normal liquid level therein adapted to vaporize liquid in indirect heat exchange relationship with said coil and thereby create pressure in the reservoir, a liquid outlet conduit in communication at one end thereof with said reservoir substantially below said heating coil and at the opposite end with said liquid path of flow of the heat exchanger, a fluid conduit for conducting fluid to be heated, said fluid conducting means having a fluid inlet and a fluid outlet, another heat exchanger providing a liquid path of flow with a liquid inlet and a liquid outlet, the other heat exchanger being positioned in indirect heat exchange relationship with fluid flowing in the fluid conduit for conducting fluid to be heated, means for conducting heated liquid from the first-mentioned heat exchanger to the inlet of the liquid path of flow of the other heat exchanger, conduit means for conducting liquid from the outlet of said other heat exchanger, said last-mentioned conduit means being in communication at one end thereof with the outlet of the other heat exchanger and at the opposite end thereof with the liquid outlet conduit intermediate the opposite ends of said liquid outlet conduit, circulating means associated with said last-mentioned conduit means for circulating liquid therethrough, and control means associated with the heating coil and adapted to control the generation of vapor and pressure within the reservoir to maintain the liquid therein below its boiling point.

5. Heat exchange apparatus for heating air to support combustion in a vapor generator having a combustion chamber by flowing said air and a liquid in indirect heat exchange relationship with one another, means for firing said chamber, a combustion gas outlet, and vapor generating means in heat exchange relationship with gases of combustion, the vapor generator having a vapor outlet, said heat exchange apparatus comprising a heat exchanger providing a liquid flow path and positioned in heat exchange relationship with gases of combustion passing from the combustion chamber to said gas outlet, a liquid reservoir disposed at a higher elevation than said heat exchanger, said reservoir being so constructed and arranged that liquid therein is normally maintained under pressure, a heating coil below the normal liquid level in said reservoir and adapted to generate vapor by heating the liquid and thereby create pressure in the reservoir, liquid conduit means through which liquid is conducted from the reservoir into said flow path of the heat exchanger, air conducting means for conducting air to the combustion chamber, said air conducting means having an air inlet adapted to receive air to be heated and air outlet in communication with the combustion chamber, another heat exchanger providing another liquid flow path, said other liquid flow path having a liquid inlet and a liquid outlet, the other heat exchanger being positioned in heat exchange relationship with air passing from the air conducting means inlet to the air conducting means outlet, means for conducting heated liquid from the first-mentioned heat exchanger to the inlet of said other heat exchanger, a pump having its suction in communication with the outlet of said other heat exchanger and its discharge in communication with the reservoir, control means associated with the heating coil and adapted to control the generation of vapor and pressure within the reservoir to maintain the liquid therein below its boiling point, a motor for actuating said pump, and other control means associated

air inlet adapted to receive air to be heated and air outlet in communication with the combustion chamber, another heat exchanger providing another liquid flow path, said other liquid flow path having a liquid inlet and a liquid outlet, the other heat exchanger being positioned in heat exchange relationship with air passing from the air conducting means inlet to the air conducting means outlet, means for conducting heated liquid from the first-mentioned heat exchanger to the inlet of said other heat exchanger, a pump having its suction in communication with the outlet of said other heat exchanger and its discharge in communication with the reservoir, control means associated with the heating coil and adapted to control the generation of vapor and pressure within the reservoir to maintain the liquid therein below its boiling point, a motor for actuating said pump, and other control means associated with the motor and with said vapor outlet and adapted to control the motor and thereby control the speed of the pump in response to the flow of vapor through the vapor outlet.

6. Heat exchange apparatus for heating air to support combustion in a vapor generator having a combustion chamber by flowing said air and a liquid in indirect heat exchange relationship with one another, means for firing said chamber, a combustion gas outlet, and vapor generating means in heat exchange relationship with gases of combustion, the vapor generator having a vapor outlet, said heat exchange apparatus comprising a heat exchanger providing a liquid flow path and positioned in heat exchange relationship with gases of combustion passing from the combustion chamber to said gas outlet, a liquid reservoir having a top and bottom and a normal liquid level intermediate said top and bottom, said reservoir being so constructed and arranged that liquid therein is normally maintained under pressure, a heating coil within said reservoir below the normal liquid level and above said bottom of the reservoir, a baffle disposed above the bottom of the reservoir and below the said heating coil, the baffle dividing the reservoir into upper and lower compartments and having a liquid opening therein through which said compartments communicate with one another, said coil being adapted to vaporize the liquid in the upper compartment and thereby create pressure in the reservoir, means through which liquid is conducted from the lower part of the reservoir into said flow path of the heat exchanger, air conducting means for conducting air to the combustion chamber, said air conducting means having an air inlet adapted to receive air to be heated and air outlet in communication with the combustion chamber, another heat exchanger providing another liquid flow path, said other liquid flow path having a liquid inlet and a liquid outlet, the other heat exchanger being positioned in heat exchange relationship with air passing from the air conducting means inlet to the air conducting means outlet, means for conducting heated liquid from the first-mentioned heat exchanger to the inlet of said other heat exchanger, a pump having its suction in communication with the outlet of said other heat exchanger and its discharge in communication with the reservoir, control means associated with the heating coil and adapted to control the generation of vapor and pressure within the reservoir to maintain the liquid therein below its boiling point, a motor for actuating said pump, and other control means associated

with the motor and with said vapor outlet and adapted to control the motor and thereby control the speed of the pump in response to the flow of vapor through the vapor outlet.

7. Heat exchange apparatus for heating air to support combustion in a vapor generator having a combustion chamber by flowing said air and a liquid in indirect heat exchange relationship with one another, means for firing said chamber, a combustion gas outlet, and vapor generating means in heat exchange relationship with gases of combustion, the vapor generator having a vapor outlet, said heat exchange apparatus comprising a heat exchanger providing a liquid flow path and positioned in heat exchange relationship with gases of combustion passing from the combustion chamber to said gas outlet, a liquid reservoir so constructed and arranged that liquid therein is normally maintained under pressure, a heating coil below the normal liquid level in said reservoir and adapted to generate vapor by heating the liquid and thereby create pressure in the reservoir, a liquid outlet conduit in communication at one end thereof with said reservoir substantially below said heating coil and at the opposite end with said liquid path of flow of the heat exchanger, air conducting means for conducting air to the combustion chamber, said air conducting means having an air inlet adapted to receive air to be heated and air outlet in communication with the combustion chamber, another heat exchanger providing another liquid flow path, said other liquid flow path having a liquid inlet and a liquid outlet, the other heat exchanger being positioned in heat exchange relationship with air passing from the air conducting means inlet to the air conducting means outlet, means for conducting heated liquid

from the first-mentioned heat exchanger to the inlet of said heat exchanger, a pump having its suction in communication with the outlet of said other heat exchanger and its discharge in communication with the liquid outlet conduit intermediate the opposite ends of said liquid outlet conduit, control means associated with the heating coil and adapted to control the generation of vapor and pressure within the reservoir to maintain the liquid therein below its boiling point, a motor for actuating said pump, and other control means associated with the motor and with said vapor outlet and adapted to control the motor and thereby control the speed of the pump in response to the flow of vapor through the vapor outlet.
